Fig. 2

The opposite side of the mat of that shown in Figure 1 is indicated by Figures 2 to 4 inclusive, the same having a flat unornamented surface extending entirely around the marginal edge of the mat and having a recessed flat unornamented surface disposed inwardly from the marginal edge of the mat.

I claim:

The ornamental design for an automobile floor mat, substantially as shown and described.
